UNITED STATES PATENT OFFICE.

FREDERICK WILLIAM JONES, OF LOS ANGELES, CALIFORNIA.

WATER-PRESSURE UNDERREAMER.

Application filed November 7, 1923, Serial No. 673,282. Renewed February 29, 1928.

This invention relates to well cutting or boring tools and is more particularly directed to underreamers utilized for enlarging the bore of the well to permit the lowering of a well casing.

An object of this invention is to provide a form of well cutting or boring device with cutters, the relative positions of which can be positively controlled at will from the top of the well so that the cutters may be advanced or retract from the cutting or reaming position at any time and without necessarily changing the vertical position of the underreamer in the well.

Another object of this invention is to provide a cutting device for wells provided with cutters actuated by means which will yield when the cutter encounters an over-load or commences to ream more rapidly in the hole than the safety of the cutting or reaming device permits so that the cutters of the device may automatically retract from the cutting position on the over-load to preserve the cutter and reaming device.

Another important object of this invention is to provide a cutting device or an underreamer with hydraulic means for advancing or retracting the cutter of the device to or from the reaming position, which hydraulic means may be controlled and operated from the top of the well without requiring any vertical motion of the reaming device to effect the operations of the cutters.

Various other objects and advantages of this invention will be apparent from the following description of a preferred example embodying the invention and will present themselves through use or the practice of the invention.

In the drawings, Figure 1 is an elevation of the preferred embodiment of the invention.

Fig. 2 is a vertical longitudinal section of the underreaming device shown in Figure 1 taken at right angles to Figure 1 and illustrating the reaming device in position in a well hole with the cutters translated to the reaming position.

Fig. 3 is a section similar to Figure 2 with the cutters illustrated in the non-reaming position and with the lower section of the reaming device broken away.

Fig. 4 is a vertical longitudinal section at right angles to Figure 3,

Fig. 5 is a transverse section with the cutters in the reaming position.

In the drawings, 2 designates the body portion of the device which carries the operating elements of the tool, said body is preferably provided with a tool joint 3 at the top by which the device may be attached to a stand of drill pipe indicated by 4 and with a similar tool joint 5 in its lower end to which other sections of the pipe or tools, such as indicated at 6, may be attached. The body 2 is provided with a vertical bore 7 extending from the upper end of the body substantially midway through the body, which bore 7 is joined to a reduced bore 8, which provides a spring receiving chamber. From the bore or spring receiving chamber 8 a flushing duct 9 extends downwardly and connects with the opening in the lower tool joint 5. 10 indicates two opposed water ducts which communicate with the bore 7 of the device near the upper tool joint 3 and likewise communicate with the flushing duct 9 so that a small flushing passage-way is provided around the other operating elements of the reaming device or tool.

11 indicates a hydraulic piston mounted in the bore 7 of the body and thus adapted to be translated in a vertical direction relative to the body 2. Preferably said piston is provided with one or more packing rings 12 between the piston and walls of the body 2. The lower section of the piston 7 engages a seat 13 which is yieldingly urged upward in the reaming device by a coil spring 14 seated in the spring receiving chamber 9.

15 indicates two opposed cutters mounted by the body which cutters are adapted to be translated to and from a reaming or cutting position. Said cutters are preferably of plate shape or form and disposed to move in a horizontal plane. The cutters are preferably of a length substantially equal to the width of the body 2 and are supported in transverse ways 16 in the body so that the same may be translated in a direction radial with respect to the body to expose their cutting edges. The piston 11 of the device is provided with a flat walled opening 17 in its lower end through which the cutters 15 pass, said opening 17 being of a width substantially equal to the combined width of the cutters 15 so that the

cutters engage the flat walls and are firmly held against tilting in the device.

To provide means for actuating said cutters to and from the reaming position by the motion of the piston 11, said piston is preferably provided with members in form of pins 18 extending through the lower section of the piston and transversely to the plates 15. said members or pins 18 extend through and engage the walls of angled cam-ways 19 in the cutters 15, the cam-ways in each cutter extending in the same parallel direction, but angled in a direction opposed to the cam-ways in the opposed cutter 15. The cutting edges of the cutters 15 are each provided with one or more débris by-passes 20 positioned closely adjacent the cutting edge of the same so that the débris cut from the well wall may pass through such by-passes 20 and be prevented from packing against the cutting edge of the cutters 15.

In operation the spring 14 of the device normally urges the piston 11 towards the upward position. The members or pins 18 are thus urged against the angled cam-ways 19 of the cutters translating the cutters to the non-reaming position, as indicated in Figure 3, where the cutting edges of the cutters 15 are held from protruding from the walls of the body 2 of the device and the same may be readily lowered through a casting to the position where it is desired to ream. Fluid is then pumped down the stand of pipe against the top of the piston 11 which under sufficient pressure is forced downward against the coil spring 14, forcing the pin 18 against the walls of the angled cam-ways 19 in the cutters 15, thereby causing the cutting edges of the cutters to be translated radially beyond the outer walls of the body and into the cutting positions as shown in Figure 2, where at the cutting edges of the opposed cutters are on opposed sides of the body 2 of the underreamer. The underreamer is then rotated to cut or ream the hole while the water pressure is maintained on the piston 11. It is not necessary to vertically translate the body of the underreamer to translate the cutter 15 of the reaming device to and from the reaming position, but the position of the cutters may be controlled at will from the top of the well by proper application of the fluid or hydraulic pressure on the underreamer.

It is to be seen also that I have provided a form of cutting device wherein the cutters

may be yieldingly maintained in the reaming position by proper application of the hydraulic pressure on the piston 11, but such cutters are not necessarily positively locked in such reaming position during the reaming or cutting operation but may yield under an excess load or inthrust to retract the cutting edge from the formation and thus under such excess load the cutting edge of the reamer will not be destroyed and the life of the cutter accordingly increased.

While I have described one form in which this invention may be embodied, various modifications may be made in the form and details of construction of the device without departing from the spirit of the invention.

This invention is of the scope set forth in the accompanying claims.

I claim:

1. A rotary underreamer comprising a body, a rigid cutter mounted by the body, means for translating the cutter to change the position of its cutting edge relative to the axis of the body, and a débris by-pass cut in said cutter back of its cutting edge.

2. In a rotary underreamer, the combination of a body, a hydraulic operated piston mounted to reciprocate vertically in said body, a spring normally urging the piston to upward position, vertical slots in the piston and body, opposed plate forming cutters positioned in said slots, the cutters being radially movable to and from a reaming position, pins carried by the piston and engaging angled cam-ways in the cutters operative to actuate the cutters through reciprocation of the hydraulic piston.

3. In a rotary underreamer the combination of a body, a hydraulic operated piston mounted to reciprocate vertically in said body, a spring below the piston normally urging the piston to an upward position, registering vertical slots in the piston and body, opposed plate-form cutters positioned in said slots, the cutters being radially movable to and from a reaming position and restrained against vertical movement by engagement with the ends of the vertical slots in the body, pins carried by the piston and engaging angled camways in the cutters thereby operative to actuate the cutters upon reciprocation of the hydraulic piston.

Signed at Los Angeles, California, this 31st day of October, 1923.

FREDERICK WILLIAM JONES.
